UNITED STATES PATENT OFFICE.

CARL SCHEVITZ, OF JACKSONVILLE, FLORIDA.

EXPANSIBLE SHOE LAST.

1,427,024.

Specification of Letters Patent. Patented Aug. 22, 1922.

Application filed August 29, 1921. Serial No. 496,352.

To all whom it may concern:

Be it known that I, CARL SCHEVITZ, a citizen of the United States, residing at Jacksonville, in the county of Duval and 5 State of Florida, have invented new and useful Improvements in Expansible Shoe Lasts, of which the following is a specification.

This invention relates to shoe stretching means, the present invention being an improvement over that forming the subject matter of an application filed by me on Feb. 21, 10 1921, Serial No. 446,654.

The general object of the present invention is to reduce the size of the device so 15 that it can be used in small sized shoes such as those worn by ladies and children by eliminating many of the parts used in the former device and at the same time simplifying the construction and operation of the device.

Another object of the invention is to make 20 the heel member vertically adjustable so that the device can be used with shoes having high heels or low heels.

A further object of the invention is to 25 make the instep stretching member vertically adjustable and to give the toe stretching member a certain amount of play so that it will adjust itself on the sole as it is being forced into the toe.

This invention also consists in certain 30 other features of construction and in the combination and arrangement of the several parts, to be hereinafter fully described, illustrated in the accompanying drawings 35 and specifically pointed out in the appended claims.

In describing my invention in detail, reference will be had to the accompanying drawings wherein like characters denote like 40 or corresponding parts throughout the several views, and in which:—

Figure 1 is an elevation of the invention.

Figure 2 is a similar view with one of the side plates removed and some of the 45 parts in section.

Figure 3 is a section on approximately the line 3—3 of Figure 6.

Figure 4 is a section on approximately the line 4—4 of Figure 6.

Figure 5 is a top plan view.

Figure 6 is a section on approximately the line 6—6 of Figure 4.

Figure 7 is a section on approximately the line 7—7 of Figure 2.

Figure 8 is a detail view of the key for operating the device.

Figure 9 is a detail view of the means for connecting the operating lever for the toe stretching member with its actuating shaft.

In these views 1 indicates a frame which is formed in the general shape of a shoe and consists of a vertical part and a toe part which extends forwardly from the lower end of the vertical part. The side pieces of the toe part of the frame are provided with the 60 slots 2. A channel shaped frame 3 is slidably mounted at the front of the upper part of the frame, said frame being adjusted vertically by means of the screw shaft 4 which engages the nut 5 on frame 3 and which is 65 rotatably supported at the top of the main frame by the collars 6, said shaft having a square end 7 for receiving the socket of the key 8, said key being shown in Figure 8. Frame 3 is provided with projections 3' 70 which engage slots 9 in the main frame. The frame 3 is provided with a curved depending part 10 to which the instep stretching member 11 is pivoted. Thus the instep member 75 can be tilted so that the device can be placed in the shoe and then the member is swung back upon the depending part 10 and by raising the frame 3 by means of the shaft 4 and the key this member 11 can be brought against the instep of the shoe to stretch the 80 same. It will be seen that the instep member is moved bodily so that the instep of the shoe can be stretched to any desired extent. 85

A lever 12 is swung from a shaft 13 by means of the links 14. This lever has its 90 lower end curved to conform to the toe part of the main frame and its lower end is pivoted to a link 15 which passes through an opening in the toe end of the frame and this link is pivoted in turn to the stem 16 of the 95 toe stretching member 17. This connection of the toe member with its operating lever permits the toe member to adjust itself in the toe as it is being moved. The upper end of the lever 12 is pivoted to a yoke member 18 which is swiveled to the screw shaft 19 which passes through a nut 20 in the top of the main frame and has a square upper end for receiving the key 8. The yoke member is 100 guided in the main frame by having its extensions 18' extending through slots 21 in the main frame. This yoke member is so formed that it will engage the inner walls of the main frame as well as the walls of the slots 21 and thus prevent bending of the 105 parts and properly guide the parts in their movement. 110

The means for actuating the side stretching members 22 consists of levers 23 and 24 arranged on each side of the toe stretching members, each lever 24 being swung from shaft 13 by the slotted link 25. The lower ends of the levers 23 and 24 are bent at right angles, as at 26, and their extremities are provided with notched ears 27 which engage the slots 2 in the toe part of the main frame.

10 Lever 24 is provided with a horizontal ear 28 which engages a notch 29 in the upper edge of lever 23, these parts being designed to permit a certain amount of movement of lever 24 in relation to lever 23 but as soon as the ear strikes one end or the other of the notch both levers will move in unison. Lever 23 has its rear end 23' provided with rack teeth upon its upper edge and passing through a slot in the rear part of the main frame.

15 The upper ends of levers 24 are pivoted to brackets 30 which are swiveled to the lower ends of the screw shafts 31 which pass through screw threaded holes in a cross bar 25 32 which is carried by the main frame and these screw shafts have square upper ends for engaging the key. The brackets 30 have parts engaging the main frame and the yoke member 18 for guiding and preventing 30 bucking of the movable parts. The rotation of the screw shafts 31 will actuate the levers 24 so as to move the bent end 26 of each lever towards or away from part 26 of its companion levers 23. This independent movement of lever 24 is limited, however, for as soon as ear 28 engages either end of the notch 29 in the companion lever, said companion lever will be caused to move with the actuating lever.

35 40 The side stretching members 22 are provided with the toggle levers 22', as described in the before mentioned application, but the ends 22" of these levers are reduced so that when they are gripped between the parts 26 45 the member 22 will be moved to a greater extent than the member shown in the before mentioned application. These toggle levers are passed between the ears 27 and between the parts 26 of the actuating levers as described in the former application so that the side stretching member can be adjusted along the device by the actuating lever and when it has been properly adjusted the lever 23 is locked in position by the locking member 32 engaging the rack teeth on lever 23 which prevents further movement of lever 23 50 so that further movement of the companion lever 24 will cause the parts 26 to approach each other and thus expand the toggle levers 55 of the side stretching member by forcing the ends 22" of said levers together. Thus the shoe is stretched at the desired place. Part 60 65 32 is similar to that described in the before mentioned application and is slidably arranged at the rear of the frame. This part

is actuated by the handle 33 which extends through an opening in the top of the frame and which has a reduced portion, engaging shoulders on the handle, for holding the same in raised position and the part 32 out of engagement with the rack teeth. As before stated these parts are similar to those described in the before mentioned application. This arrangement of parts will permit the side stretching member to be moved to any desired position lengthwise of the shoe and when locked in this position to permit the parts to be actuated to force the stretching member outwardly to stretch the shoe.

70 75 80 85 90 95 100 105 110 The heel frame 34 is vertically adjustable on a yoke 45 by being screwed to the yoke by the screw 46 which passes through a longitudinal slot 47 in the heel frame. Thus this frame can be adjusted vertically so as to make the device adjustable for shoes having heels of different heights. The heel frame is also movable towards and away from the rest of the device by means of the handle member 48, the lever 49 which engages the slotted lug 50 and the handle supporting member 51, these parts being substantially the same as shown in the before mentioned application. The arms 52 of the yoke are provided with rack teeth and these arms are slidably mounted in the guides 53 formed in the sides of the main frame. The rack teeth are engaged by the locking plate 54, slidably mounted at the rear of the main frame and which is normally held in engagement with the rack teeth by the spring 55 located on the rod 56 which is pivoted to the member 51 and has its lower end engaging the locking plate 54 so that when the handle member 48 is actuated the locking plate will be raised to permit the lever 49 to move the parts inwardly. As all of these parts are substantially the same as shown in the before mentioned application it is not necessary to describe them in detail.

115 120 125 The parts are enclosed by the side plates 57 and the bottom plate 58.

It will thus be seen that the construction of the present application is such that the parts composing the same are compactly assembled so that the device can be made small enough to fit ladies' and children's shoes and that the heel frame can be adjusted to suit shoes with high and low heels. The toe of the shoe can be stretched by the toe stretching member and either or both sides of the shoe can be stretched for bunions or the like by the side stretching members, the operating parts of these members being substantially the same as those shown in the before mentioned application.

It is thought from the foregoing description that the advantages and novel features of my invention will be readily apparent.

I desire it to be understood that I may

make changes in the construction and in the combination and arrangement of the several parts, provided that such changes fall within the scope of the appended claims.

5 What I claim is:—

1. A shoe last of the class described comprising a main frame, a heel frame slidably connected with the main frame, manually operated means for adjusting the heel frame 10 and means permitting the heel frame to be adjusted vertically to suit shoes with high and low heels, such means consisting of a supporting member for the heel frame and a screw and slot connection between the

15 same and heel frame.
2. A shoe last of the class described comprising a main frame composed of a vertical part and a forwardly and downwardly curved toe part, a heel frame slidably connected with the rear of the main frame, manually operated means for adjusting the heel frame towards and away from the main frame, means to permit adjustment of the heel frame vertically, shoe stretching parts 20 associated with the toe part of the main frame and actuating means within the main frame connected with such stretching parts.

3. A shoe last of the class described comprising a main frame composed of a vertical part and a forwardly and downwardly curved toe part, a heel frame slidably connected with the rear of the main frame, manually operated means for adjusting the heel frame towards and away from the main 35 frame, means to permit adjustment of the heel frame vertically, shoe stretching parts associated with the toe part of the main frame, and actuating means within the main frame connected with such stretching parts, such actuating means including levers swing- 40 ingly supported within the main frame and screw shafts rotatably mounted in the main frame and engaging the levers.

4. A shoe last of the class described comprising a main frame including a vertical 45 part and a forwardly and downwardly curved toe part, a member vertically slidably on the front of the main frame and having a curved depending part, an instep stretching member pivotally secured to the lower 50 end of the depending part and a screw shaft

mounted in the main frame and engaging a screw threaded socket in the slidable member.

5. A shoe last of the class described comprising a main frame including a vertical part and a curved toe part, a lever swingingly supported in the main frame and having a curved lower end, a link pivotally connected with said lower end, a toe stretching member pivotally connected with the link, the toe of the main frame having a hole therein through which the link extends and a screw shaft rotatably mounted in the frame and having its lower end swiveled to the upper end of the lever. 55

6. A shoe last of the class described comprising a main frame, shoe stretching members associated therewith, a shaft in the main frame, levers arranged in the main 70 frame, links swingingly connecting the levers with the shaft, means for connecting the lower ends of the levers with the stretching members and screw shafts supported in the main frame and connected with the upper 75 ends of the levers.

7. A shoe last of the class described comprising a main frame, a pair of levers swingingly supported therein, a companion lever associated with each lever of the pair, said 80 levers having rightangular extensions at the lower ends, screw shafts mounted in the main frame and connected with the first levers for actuating the same, means for permitting a certain amount of movement of 85 the first levers relative to the companion levers, means for locking the companion levers against movement and a side stretching member having toggle levers connected therewith, with their extremities placed between the extensions of the levers at either 90 side of the device. 90

8. A shoe last of the class described comprising a main frame, a side stretching member, toggle links connected therewith, the 95 outer extremities of the outer links being reduced, clamping members in the frame for engaging the said reduced extremities and means for actuating the clamping members.

In testimony whereof I affix my signature. 100

CARL SCHEVITZ.
